UNITED STATES PATENT OFFICE.

ENRICO BORBONESE, OF TURIN, ITALY.

MACHINE FOR SWEEPING AND COLLECTING SNOW AND THE LIKE.

1,180,229.

Specification of Letters Patent. Patented Apr. 18, 1916.

Application filed February 10, 1912. Serial No. 676,856.

To all whom it may concern:

Be it known that I, ENRICO BORBONESE, a citizen of Italy, residing at Turin, Italy, have invented certain new and useful Improvements in Machines for Sweeping and Collecting Snow and the like; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The invention relates to a sweeping and collecting machine, especially suitable for the collection of snow or the like, comprising substantially: A vehicle, which may be a motor vehicle or a trailed one. A dredge, (or other collecting device), provided also with sweeping means, situated on the front of the vehicle and operated by the same motor which drives the vehicle, this dredge, during the progress of the vehicle and along its way, being capable of collecting entirely any dusty or granular material (as snow or the like) encumbering the road. A collecting tank situated in the vehicle and serving to contain the material dragged up by the dredge, for the purpose of discharging it to a suitable place when the said tank is full.

The accompanying drawings show by way of example a mode of applying this invention to a motor-vehicle.

Figure 1 shows in side elevation, partly in section, a first form of construction of the machine. Fig. 2 is the plan of it, and it will be seen that in the inferior half of this figure the dredge and the tank have been partially omitted for greater clearness. Fig. 3 shows a back view, and Figs. 4 and 5 show some details. Fig. 6 shows a side elevation, partly in section, of a slightly modified form of the same machine. Fig. 7 shows the plan of the frame of the vehicle. Fig. 8 is a detail.

Like characters of reference indicate like or similar parts throughout the specification and the views of the accompanying drawings.

In the sweeping and collecting machine according to the present invention, and more especially according to the first form of construction of it, (Figs. 1 to 5), the dredge or the like may be of any known type, and may be for instance constituted, as shown in the drawings, by the chains 1 for the connection of the buckets 2, by the supporting drum 3, and by the driving drum 4, whose shafts 5 and 6, (journaled on a structure formed by two longitudinal bearers 7 connected together by means of stay bolts 8), are coupled together in their movement by means of the chain 9 in engagement with the toothed wheels 10, 11 respectively keyed on the shafts 5, 6. But the dredge used in the present invention is different from the usual ones, as the back part of each bucket 2 is provided with a flat brush or longitudinal comb 12, preferably of metallic plate or wire, which brush is vertically fixed to the said chains 1, or directly fixed to each bucket 2, so as to slightly project beyond the said buckets. (See Fig. 1 and the detail shown in perspective view by Fig. 4, which shows a bucket 2 and its brush 12). In this form of construction of the machine, the buckets are suitably spaced the ones from the others, in order that the driver from his place 19 may have a sufficiently free sight along the way.

The dredge is mounted on the front of the vehicle by means of diagonal stays 13, 14, 15 and uprights 16 connected to the frame 17 of the vehicle, so that the dredge is downwardly inclined toward the front thereof. The shaft 5 of the front drum 3 is placed at such a suitable distance from the level of the road, that, while the buckets 2 in their lowest position remain at some distance from the ground in order to avoid any obstacle to their motion and breakage in consequence of stones or projections of the road, the brushes 12 on the contrary, as they project beyond the buckets, come in contact with the ground and by bending themselves produce a sweeping action. The shaft 6 of the back drum 4 is placed near the mouth of the collecting tank 18, which is mounted on the back part of the frame 17 of the vehicle. The said shaft 6 receives its motion

in the desired direction from the shaft 20 by means of the chain 21 and the toothed wheels 22, 23 respectively mounted on the shafts 6 and 20. The shaft 20 is driven by the same motor which drives the vehicle, by means of a couple of toothed wheels 24, 25 respectively keyed on the shaft 20 and on the shaft 26, which shaft 26 in its turn is driven by the motor and transmits the stress 10 to the back wheels 27 of the vehicle (Figs. 1, 2). The rotation of the shaft 20 is transmitted to the toothed wheel 23 preferably through a clutch 28, which may be operated by means of the lever 29 in order to interrupt 15 eventually the operation of the dredge (Fig. 1).

The dredge which is applied to the sweeping and collecting machine forming the object of the invention and constructed according to the first form of construction, 20 presents also the following features: On each end of the shaft 5 of the front drum is disposed a rotary disk 30 of suitable diameter to prevent the buckets 2 from touching 25 the road surface when they are in their lowermost position during operation, while the rotary disks 30 run on the surface of the road. In order to prevent the shock of the disks 30 against the surface of the road 30 during the starting up of the vehicle, there may be adopted for the shaft 5 an elastic suspension as shown in detail in Fig. 5. In this case the shaft 5 of the drum 3 is not rigidly fixed to the structure 7, but it is 35 connected to the arms 31 jointed at 32 to the frame 17 of the vehicle, so that the said shaft may be displaced inside the oblong slots 7' of the ends of the longitudinal bearers 7. The springs 33 connected to the longitudinal 40 bearers 7 and to the projections 31' of the arms 31 push constantly downward the arms 31 and consequently the shaft 5. In order to insure the complete discharge of the buckets 2 into the tank 18, there are 45 provided one or more shaking devices, constituted for instance by elastic arms 34 fixed to the axis 35 situated transversely above the tank 18. The said elastic arms 34, during the movement of the dredge come in 50 engagement with the brushes 12, and are firstly depressed and then released, so that they are compelled to strike against the bucket (shown in dotted lines in Fig. 1) which bucket is on the point of being discharged. 55

From the foregoing it will be easy to understand the manner of working of the present machine. In fact, during the forward motion of the vehicle, the dredge being 60 driven in the indicated direction, the buckets 2 come and take up the material 36 lying on the surface of the road, but they leave untouched a layer 36' the thickness of which is the same as the distance of the 65 buckets from the ground; (this has been in-

dicated by dotted lines in Fig. 1) but this layer is swept forward in the next moment by the brush or comb 12 which follows immediately the bucket, and is taken up by the next bucket, and so on. The road 70 remains in consequence perfectly clean. The material taken up by the buckets is then carried to the tank 18, from which it may be evacuated when the said tank is full. The tank 18 may be provided with a movable bottom 18' preferably formed by two parts (Fig. 3) which open themselves toward the sides of the vehicle and may be operated by means of the chains 37. 75

When the machine is destined for collecting snow, and the motor which drives the whole machine is a mechanical one, preferably of the internal combustion type, it is suitable to lead through the pipe 38 the exhaust products of the motor along the walls 85 of the double wall 18'' of the tank 18 from which they go out from 39. This arrangement produces the heating of the said walls, and insures a partial melting of the snow, which can so descend more easily inside the 90 tank 18 as well during the filling up of it as during its discharge. 95

In the form of construction of the machine as shown in Figs. 6, 7 and 8, the principal modification in the general arrangement of the construction consists in the arrangement of the driver's seat on the front of the vehicle. In consequence of this arrangement, the driver's view is perfectly free and not hindered by the buckets of the dredge, which buckets may be disposed very near to each other in order to increase the specific efficiency of the said dredge. The motor 40, which, in distinction from the first form of construction, is situated almost 100 at the center of the frame 17, serves to drive the back wheels of the vehicle through the usual change speed gear 41 and preferably by means of chains 42. The said motor, 105 preferably of the internal combustion type, may be started by means of the side crank 40', from which the stress is transmitted to the motor by means of the couple of bevel wheels 40''. The arrangement of the whole dredge or the like is slightly modified. In 110 fact, the shafts 5', 6' are not provided with drums, but each of them bears a couple of toothed wheels 3', and 4', respectively, with which come in engagement the supporting chains 1 of the buckets. Besides, the lower 115 shaft 5', instead of being elastically arranged in regard to the frame 17, is carried by the side bearings 47 fixed to the said frame. (See the detail at Fig. 8). But the said shaft 5' is capable of being controlled 120 in regard to its height, by displacing the bearings 5', by means of the screws 47', inside the slots 47'' of 47. In consequence of such arrangement it is possible to change 125 the distance of the buckets 2 from the sur- 130

face of the road without changing the tension of the chains 1, because the slots 47" of 47 are arranged perpendicularly to the oblique position of the dredge. The upper shaft 6^a is arranged slidably on the ends of the longitudinal bearers 7 by means of bearings 6', and its position may be controlled by means of tension devices 7^a serving to obtain the desired tension of the chains 1. The shaking device, whose function is to facilitate the discharge of the contents of the buckets 2 into the tank 18, is in this case constituted by a cross bar 34 (Fig. 6) connected to the upper ends of the longitudinal bearers 7 by means of the side bearings 35. The brushes 12 of the buckets 2 are caused to strike against the said bar, so that at first they are compelled to bend themselves, and then leaving the bar 34 they shake the body of the corresponding bucket, which is so compelled to discharge its contents.

The control of the dredge is operated in such a manner that the transmission of the power of the motor is preferably directed to the front shaft 5^a of the said dredge. This transmission, with a great reduction of velocity, may be effected for instance by means of the shaft 20^a, which with its worm 3 engages the worm-gear 44 directly mounted on the motor shaft. From the shaft 20^a, by means of the toothed wheels 23 and the chains 21 the power is transmitted to the toothed wheels 22^a keyed on the counter shaft 45, from which, by means of the wheel 6 and the chain 48, the movement is transmitted to the toothed wheel 10^a keyed on the shaft 5^a of the dredge. The hand operated claw coupling 28, serving to interrupt temporarily the working of the dredge, is preferably arranged on the counter shaft 45, and serves to temporarily couple together the shaft and the toothed wheel 46 which is loosely mounted on shaft 45. This arrangement is made for the purpose of enabling the operator to start or stop the dredge, or in other words, the running of the buckets, at any time while the machine is in motion.

On the front sides of the vehicle there are arranged two walls 49 preferably constructed of metallic plate, which are curved outward and may be substantially considered as extensions of the fixed side walls 50 serving to close laterally the body of the dredge. The said walls 49 are preferably arranged at 49' to the side walls 50, and are prevented from swinging outwardly too far by means of any suitable device, as for instance chains 51 fixed to an eye 52 (see Fig. 1) of the frame and attached to hooks 49" fixed to 49. The said walls 49 collect and direct to the dredge the material (snow or ice like) which lies along the way of the vehicle, and that in a greater or smaller quantity according to the greater or smaller

divergence of the said walls, as shown respectively in full and in dotted lines in Fig. 7. When the said walls are completely closed and their ends are brought into contact, as has also been shown in dotted lines 70 in Fig. 7, they work as a snow plow, which position is of great utility when the transport of the machine must be effected.

It is obvious that the invention may be applied to vehicles driven by any kind of 75 motor, and not only by an internal combustion motor as shown in the annexed drawings, Fig. 7 and that the machine may be used not only for clearing away the snow on the roads of the towns, but also on the rail- 80 ways, when it acts as a snow plow as indicated in dotted lines Fig. 7.

Claims:

1. In a dredge, the combination of endless chains, buckets attached to said chains at 85 regular intervals, said buckets being provided with scraping edges, a brush mounted directly to the rear of each bucket independently thereof and slightly projecting beyond the 90 bucket, and a shaking device at the discharge end of said dredge in coöperation with said brushes.

2. In a dredge, the combination of endless chains, buckets attached to said chains at 95 regular intervals, said buckets being provided with scraping edges, a brush adjacent each bucket secured to the chain independently of the bucket and directly to the rear thereof and slightly projecting beyond the 100 bucket, and a shaking device at the discharge end of said dredge, said device comprising a transverse bar mounted on the dredge for obstructing the passing brushes, whereby said brushes on their sudden release from 105 said bar, will cause the respective buckets to be shaken.

3. In a dredge, the combination of endless chains, buckets attached to said chains at regular intervals, said buckets being provided with scraping edges, a brush attached 110 to a chain directly behind each bucket and independent thereof and slightly projecting outwardly beyond the buckets, whereby the buckets are prevented from contacting with the road-way while the brushes sweep the 115 road-way, said brushes being made in the form of longitudinal combs, and a shaking device at the discharge end of said dredge, said device comprising a transverse bar mounted on the dredge, said dredge being 120 adapted to serve as an obstruction for the passing brushes, whereby said brushes on their sudden release from said bar, will cause the respective buckets to be shaken.

4. In a dredge, the combination of endless chains, buckets attached to said chains at regular intervals, said buckets being provided with scraping edges, a brush secured to the chain directly behind each bucket and slightly projecting outwardly beyond the 125 130

bucket, and a shaking device for facilitating the discharge of said buckets, said shaking device comprising elastic arms, a shaft on which said arms are mounted to oscillate, said arms being suitably located so as to be struck by said brushes.

The foregoing specification signed at

Turin (Italy) this 23rd day of January, 1912.

ENRICO BORBONESE.

In presence of two witnesses:

FRANCISCO SIMONI,

JOCELYN GOUBEGRAN.
